STEPLADDER TRAY OR SHELF

Marvin M. Hickey, South Bend, Ind.

Application July 3, 1945, Serial No. 603,042

1 Claim. (Cl. 248—238)

1

This invention relates to a step ladder tray or shelf which is detachable and particularly adapted for use with stepladders that are used by housewives in cleaning their homes.

The principal object of the invention is to provide a detachable tray or shelf that will support buckets and other articles necessary for cleaning walls, windows and the like.

The present day step ladders will not accommodate more than one bucket at a time and this drawback prevents the housewife from accomplishing her job in a quick and efficient manner. With the aid of the present invention she can use two buckets, one for cleaning water and one for rinsing water.

The tray or shelf could also be used by painters, carpenters or electricians in a like manner to support any articles that are necessary to their occupation.

Another object of the invention is to provide a detachable tray or shelf which is light, strong and durable and can be quickly applied to or removed from a step ladder.

Other objects and advantages will appear as the description proceeds when taken in connection with the disclosures in the accompanying drawing in which:

Fig. 1 is a top plan view of an embodiment of the invention, partly broken away.

Fig. 2 is a side view thereof, in operative position on a step ladder shown in section.

Fig. 3 is a perspective view of the tray.

Fig. 4 is a sectional view on the line 4—4 of Fig. 1.

Fig. 5 is a top plan view of a modification of the device.

Fig. 6 is a side view thereof.

Fig. 7 is a sectional view on the line 7—7 of Fig. 5, and

Fig. 8 is a perspective view of the clamping means of the tray.

Referring more in detail to the drawings the conventional step ladder 10 formed with the usual rails 12 between which are mounted steps 14 and the top shelf 16 is set up in the usual working manner by extending the bracing legs 18 which are usually pivoted to the ladder as shown in section in Fig. 2.

The invention which is to be used in conjunction with such a step ladder comprises a large rectangular shaped tray 20 which is provided with upstanding sides 22 and ends 24 forming a continuous flange or rail around the entire periphery of the tray 20, the outer edge of which is bevelled as shown.

2

Adjacent the sides 22 the tray is provided with diametrically opposed openings 26 and in like manner diametrically opposed openings 28 are positioned adjacent the ends 24.

When the tray is to be used as shown in Figs. 1 and 2, a bolt 30 having a wing nut 32 is positioned in one of the openings 26 and inserted through the openings 34 of a spacer block 36 having a straight rear edge 38 and a triangular shaped front edge 40.

The opening 34 is positioned at the medial point of the block 36 adjacent the rear edge 38 thereof. With the openings thus positioned and the apex 42 of the front edge 40 contacting the step 14 of the ladder 10 the shelf will stay in one position and not shift laterally.

An L-shaped clamping bar 44 having the forward end bevelled at 46 and the depending end rounded at 48 is provided with an opening 50 to receive the bolt 30 and when the tray is positioned on the upper side of the top shelf 16 and the clamping bar is positioned on the lower side of the top shelf 16 the tray 20 can be firmly clamped thereon by tightening the wing nut 32.

When the device is to be used as shown in Figs. 5 and 6, bolts 30 are positioned in the openings 26 and are adapted to be received in registering opening 52 and slot 53 in the elongated clamping bar 54. Thus when the tray is positioned on the upper side of the top shelf 16 and the bar 54 is positioned on the lower side of the top shelf 16 the tray 20 can be firmly clamped thereon by tightening the wing nuts 32.

The slot 53 permits the bar 54 to be swung into or out of operative position without entirely removing the bolts 30 from the tray 20.

While the device has been shown in use with the top shelf of the ladder it can be easily placed on the steps in like manner, since the width of the tray is slightly smaller than the width of the conventional step ladder.

It is believed that from the foregoing description the operation of the device will be clearly understood without going into a more minute and detailed description of the operation thereof.

It will be seen, therefore, that there has been provided a simple but practical device which can be cheaply manufactured, will be of great help and assistance in its particular field. It comprises a few working parts that are simple to operate and will not easily wear out. It is light, portable, easily carried from one location to another and just as easily stored when not in use.

It will also be understood that the embodiment illustrated herein is merely used as an example

thereof and that various changes and modifications can be made without departing from the spirit of the invention or falling beyond the scope of the appended claim.

Having thus described the invention, what is claimed as new and desired to be secured by Letters Patent is:

A tray for attachment to a step of a step ladder comprising a rectangular bottom, a continuous flange about said bottom to form a tray, said bottom being adapted to rest upon the upper surface of the step substantially lengthwise of the same, said bottom having a pair of spaced openings transversely spaced in a plane medial of said bottom and perpendicular to the longitudinal axis of said bottom portion, each of said openings being adjacent said flange, bolt means through said openings, a clamping bar being adapted to engage the lower surface of the step and to receive one of said bolts whereby said bar is pivotally mounted on said one bolt for swinging said bar relative to the other of said bolts, said clamping

bar having a slot therein, spaced from said first bolt which is adapted to receive the other of said bolts, and clamping nuts on said bolts whereby said clamping bar and tray may be clamped to the step.
